UNITED STATES PATENT OFFICE.

FREDRIC C. SHELDON, OF NEW YORK, N. Y.

INDEX.

1,084,665.

Specification of Letters Patent. Patented Jan. 20, 1914.

Application filed February 16, 1912. Serial No. 678,008.

To all whom it may concern:

Be it known that I, FREDRIC C. SHELDON, a citizen of the United States, residing in the borough of Manhattan, city, county, and 5 State of New York, have invented certain new and useful Improvements in Indexes, of which the following is a specification.

This invention relates to indexes, and aims to provide certain improvements 10 therein.

The invention is particularly designed for use in connection with religious works wherein certain definite lessons or readings are prescribed periodically by some authoritative body. Such readings are usually 15 chosen with regard to a given line of thought and are but rarely to be found consecutively arranged in the book to which they refer. The reader is hence obliged to refer quickly 20 to separated portions of the work for each day's lesson.

The object of the present invention is to provide a temporary index which may be easily arranged in advance for a given lesson or series of lessons, so that the book may 25 be prepared in advance for the work of the succeeding week or month.

The index provided by this invention is so constructed that particular paragraphs or 30 sentences may be indicated thereon, and such marks or indications may be expunged so that the index has a practically indefinite life.

The invention also includes means where- 35 by the index pages may be quickly and easily fastened temporarily to the book without in any way defacing or harming the latter.

The invention also includes certain other features of improvement which will be here- 40 inafter more fully described.

Referring to the drawings which illustrate the invention, Figure 1 is a perspective view of a book having therein a series of index sheets constructed according to the present 45 invention, one of such sheets being shown in perspective at the right hand of the figure. Fig. 2 is a plan illustrating one method of fastening the index sheets to the book. Fig. 3 is a perspective view of the top of a book, 50 showing the ends of the series of index sheets. Fig. 4 is a plan showing a modification.

Referring to the drawings, let A indicate a book of the character described, being 55 shown as the usual bound volume having a cover *a* and a series of leaves *b*. According

to my invention I provide a series of index sheets *B* which are preferably nearly the full width and length of the sheets of the book, although they may be of any preferred shape and dimensions, so long as they are capable of carrying the indication marks and the index tabs *c* which extend beyond the edges of the sheets of the book, preferably at the front thereof.

In the preferred construction the index sheets *B* are formed of thin flexible sheets having a surface sufficiently rough to permit their being marked with a lead pencil or the like, and preferably being adapted to permit the erasure of the marks without marring the sheet. I have found in practice that celluloid or similar material answers the purpose admirably. Preferably the index sheets are opaque, in which case the user will utilize 75 the side of the sheet which is immediately opposite the printed sheet by placing lead pencil indicating marks opposite the portion of the text which forms the matter to be read. One example of such indicating 80 marks is indicated at *d* in Fig. 1. Preferably also at some convenient part on the sheet it is usual to indicate the page and lines to be read. Thus in the example shown in Fig. 1 the reading will be on page 563, 85 lines 1 to 8. According to my invention I may also employ transparent sheets constructed of transparent celluloid or other suitable material, in which case the mode of use may be slightly different, that is to say, 90 instead of the indicating marks *d* the sheet may be provided with a lead pencil mark surrounding the text appointed for the particular day. This construction is illustrated in Fig. 4. In such use the sheet will remain 95 over the printed page, and the latter read through the sheet. In the construction shown in Fig. 1 if the text is on opposite pages one side of the sheet *B* may be utilized for one page and the other side for the opposite page. When the sheets are transparent, 100 however, it is desirable to introduce two guide sheets, one for each page. The index tabs *c* may be fixed temporarily or permanently to the guide sheets, and may have 105 permanent numbers, in order that the references selected may be consecutively read.

To realize the full advantages of the invention, it is necessary to provide means for temporarily holding the index sheets in place, 110 and these means should be so constructed as to avoid as much as possible any injury to

the leaves of the book. According to the preferred form of the invention each of the index sheets is provided at its inner edge with two lugs *f*, and these lugs extend beyond the edges of the printed pages of the book and are adapted to be engaged by temporary fastening means, the preferred form of which I have illustrated. In this form the lugs are provided with apertures *g* which 10 are adapted to receive an elastic band or other flexible fastening device *h*, the ends of which are provided with means for fastening them to some convenient part of the book, preferably the covers *C*. As illustrated, these fastening means comprise two wire members *j* at each side of the book which are formed at their outer ends with hook portions *k* which are passed through the ends of the elastic band, the bodies of 20 the wire members being located between the printed matter and the covers. The hooks *k* are so formed as to pass outside of the book and engage the covers, and also to engage the flexible band *h*. At this point there is 25 usually formed a crease or at least a portion of less thickness than the covers so that the wire members *j* are held fixedly in place. Each of the opposite wire members is also preferably provided with an eye portion *l*, the two eye portions being connected together by a thread or small elastic band. In order to assist in preventing the wire members from twisting or turning, I preferably form each with a bent portion *m* which lies 30 flat between the covers and printed matter. The provision of the elastic band *h* is important in that it permits the book to be opened without placing any additional strain upon the sheets, the band expanding 35 at the place of opening. Furthermore, the band assists in holding all of the index sheets firmly in position between the inner edges of the leaves, so that the sheets are not liable to work outwardly in use. In order to 40 prevent displacement in a longitudinal direction the lugs *f* extend rearwardly to a point beyond the rear edge of the sheet whereby to engage the top and bottom edges of the sheets as best illustrated in Fig. 1.

45 In practice the index sheets will be furnished in such number as corresponds to the number of lessons to be read in a definite period, as for instance one week. Each of the sheets may advantageously be provided 50 with permanent numbers on their tabs, and the user will take the appointed list and fix each sheet in its order at the proper place within the book, making such temporary marks thereon as will indicate definitely the 55 appointed lesson. One pair of the wire retaining members *j* will then be adjusted in place and the ends of two elastic bands passed through the loops thereof, whereupon 60 the opposite ends may be threaded through 65 the apertures *g* in the series of sheets, this

operation being assisted if desired by a fine hook which is passed through the series and engaged with the rubber band so that the latter may be pulled through the apertures. The end of each band is then engaged by 70 hooks *k* of the other pair of retaining members, the latter being then adjusted in place. After this is done the reader can without difficulty turn consecutively to each reading, beginning at tab #1 at the top and working 75 down one tab at each successive reference. If desired the tabs may be printed with the day of the week, or the date, or other suitable matter which will serve to indicate the precise point at which the book is to be 80 opened.

The invention provides a construction which is of great convenience in that it enables a series of reference readings to be indicated at one time without injury to the 85 book or defacement of the pages. The record is permanent so long as the sheets remain in their positions, but the latter may be removed and used indefinitely by erasing the indication marks.

90 While I have described certain embodiments of the invention, I do not wish to be limited thereto as various changes may be made therein without departing from the invention. For instance, the sheets may be 95 formed of paper or other suitable material and instead of the marks *d*, etc., being applied by the user, they may be printed upon the sheets, in which case a new set will be furnished at the beginning of each period. The mode of attachment to the book may 100 also be considerably varied without departing from the invention.

105 While the invention has been described in connection with works of a particular character it will be understood that it may be employed in connection with other works which are found useful.

What I claim is:—

1. An index of the character described 110 comprising a series of flexible leaves, adapted to be temporarily placed within a book, said leaves being of substantially the length and breadth of the leaves of the book in which they are to be placed, each of said 115 sheets having perforated lugs extending beyond the leaves of the book, means passing through said perforations for temporarily holding the sheets in place, said means comprising elastic bands, and means for connecting said bands to the body of the book.

120 2. An index of the character described comprising a series of flexible leaves, adapted to be temporarily placed within a book, said leaves being of substantially the length and breadth of the leaves of the book in which they are to be placed, each of said 125 sheets having perforated lugs extending beyond the leaves of the book, means passing through said perforations for temporarily 130

holding the sheets in place, said means comprising elastic bands, and means for connecting said bands to the body of the book, said last-named means comprising book members adapted to lie between the covers of the book and to engage the exterior of the book, and said members adapted to engage said elastic bands.

5. An index of the character described comprising a series of flexible leaves, adapted to be temporarily placed within a book, said leaves being of substantially the length and breadth of the leaves of the book in which they are to be placed, each of said 10 leaves having at its ends two lugs adapted to extend beyond the leaves of the book, said lugs also extending rearwardly beyond the rear edge of each sheet and each lug being perforated, and flexible means passing 15 through said perforations and engaging the body of the book to hold said sheets in place.

4. An index of the character described comprising a series of index sheets formed of flexible material adapted to be marked, 25 and adapted to permit the erasure of the marks without injury to the sheets, each of said sheets having a pair of lugs at its rear edge extending beyond the edges of the leaves of the book, each of said lugs also extending rearwardly of the edges of the sheet, 30 said lugs being perforated, two pairs of hooks, each adapted to lie between the covers of the book and each having a hook adapted to engage the outer side of the cover, flexible bands engaged by said hooks and passing 35 through said perforations, and the hooks of each pair having means for connection whereby to hold them in place.

5. The combination with a series of index 40 sheets of members for holding said sheets in place, said members being constructed of wire having hook portions adapted to engage the exterior of the book, and eye portions adapted to lie along the inside of 45 the covers and lie flat against the leaves when the book is closed.

6. An index of the character described, comprising a series of flexible leaves adapted to be temporarily placed within a book, said 50 leaves being flat and of substantially the length and breadth of the leaves of the book in which they are placed, and having indicating provisions extending beyond the edges of the sheets, said leaves having indications on the body thereof opposite the beginning and ending 55 of any particular matter at any transverse or longitudinal point on the printed pages in conjunction with which they are adapted to be used.

beginning and ending of any particular matter at any transverse or longitudinal point on the printed pages in conjunction with which they are adapted to be used.

7. An index of the character described, 60 comprising a series of flexible leaves adapted to be temporarily placed within a book, said leaves being flat and of substantially the length and breadth of the leaves of the book in which they are placed, and having 65 indicating provisions extending beyond the edges of the sheets, said leaves being of celluloid and adapted to temporarily receive and have readily obliterated therefrom indications on the body thereof opposite the 70 beginning and ending of any particular matter at any transverse or longitudinal point on the printed pages in conjunction with which they are adapted to be used.

8. An index of the character described, 75 comprising a series of flexible leaves adapted to be temporarily placed within a book, said leaves being flat and of substantially the length and breadth of the leaves of the book in which they are to be placed, and 80 having indicating provisions extending beyond the edges of the sheets, said leaves being of celluloid and adapted to temporarily receive and have readily obliterated therefrom indications on the body thereof, and 85 adapted to surround and embrace any particular matter on any part of the printed pages in conjunction with which they are adapted to be used.

9. An index of the character described, 90 comprising a series of flexible leaves adapted to be temporarily placed within a book, said leaves being flat and of substantially the length and breadth of the leaves of the book in which they are placed, and having 95 indicating provisions extending beyond the edges of the sheets, said leaves being transparent and having indications on the body thereof opposite the beginning and ending of any particular matter at any transverse 100 or longitudinal point on the printed pages in conjunction with which they are adapted to be used.

In witness whereof, I have hereunto signed my name in the presence of two subscribing witnesses.

FREDRIC C. SHELDON.
